UNITED STATES PATENT OFFICE.

CHARLES C. HOGEN, OF CLEVELAND, OHIO.

PILOT-BEAM.

No. 928,200.

Specification of Letters Patent.

Patented July 13, 1909.

Application filed March 2, 1907. Serial No. 360,136.

To all whom it may concern:

Be it known that I, CHARLES C. HOGEN, a citizen of the United States, resident of Cleveland, county of Cuyahoga, and State 5 of Ohio, have invented a new and useful Improvement in Pilot-Beams, of which the following is a specification, the principle of the invention being herein explained and the best mode in which I have contemplated 10 applying that principle, so as to distinguish it from other inventions.

My invention relates to draw-gear and particularly to draw-gear for locomotives.

It is the object of the invention to over- 15 come certain difficulties, later to be described, that seem more or less inherent in the type of such gear at present in use on our rail-ways.

To the accomplishment of this object said 20 invention consists of means hereinafter fully described and specifically pointed out in the claims.

The annexed drawings and the following 25 descriptions set forth in detail certain means embodying the invention, such disclosed means constituting but one of various mechanical forms in which the principle of the invention may be used.

In said annexed drawings: Figure 1 is a 30 broken view, partly in plan and partly in horizontal cross-section, of the pilot end of a locomotive showing one embodiment of my improved construction; Fig. 2 is a vertical longitudinal cross-section of the same, 35 taken on the line 2—2, Fig. 1; Fig. 3 is a vertical transverse cross-section of the same, taken on the line 3—3, Figs. 1 and 2; Figs. 4 and 5 are respectively a plan view and a 40 vertical transverse cross-section of a locomotive bumper beam of wood and showing the adaptation of my invention thereto.

In all locomotives, and particularly in 45 switching locomotives, considerable difficulty has been encountered in devising means for satisfactorily coupling cars to the locomotive's pilot end. This difficulty, particularly emphasized in the case of switching locomotives, arises in the first place from the 50 relatively short wheel base, which causes the ends of the locomotive to extend beyond or overhang such base, and in the second place from the peculiar construction of the under frame of the locomotive and the forward boiler support, whereby the only practical 55 manner of attaching the draw bar and

coupler has been directly to the transversely disposed bumper beam that forms the terminal member of such frame. It is hence possible to provide for only a very limited pivotal movement of the coupler, that, for 60 instance to be had within the confines of the coupler pocket ordinarily provided in the pilot beam for the reception of the coupler proper. A lateral swing of approximately ten inches is the maximum that has hitherto 65 been achieved in this prevailing type of construction. This amount is scarcely sufficient to allow the coupling to accommodate itself to the sharper curves of the main line tracks and is altogether insufficient to serve in 70 switching operations, where, as has been explained, engines of shorter wheel base and correspondingly greater overhang are employed, and where curves of much shorter radius are to be encountered. A constant 75 source of annoyance hence exists arising from the frequent derailments and broken couplers incident to the employment of the present type of coupler.

It need scarcely be stated that I am fully 80 aware of the use of push-bars, and of jointed pilot beams consisting of a plurality of pocket members mounted one within the other. Aside from structural difficulties inherent in both these types of draw-gear, they 85 obviously do not permit of the use of automatic coupling devices such as are now quite generally required by statutory enactment and as well as by humanitarian considera- 90

tion. Referring then to Figs. 1, 2 and 3 of the drawings, A, A' will be seen to designate the upper and lower longitudinal members, respectively, of the locomotive frame. Between these, as will be understood, are 95 mounted the boxes in which the wheel axles are journaled, and upon them is supported the fire box and boiler of the locomotive. The forward ends of the frame members A, A' are joined by the bumper beam B, 100 which in the figures of reference is shown as of a novel form designed especially for the accommodation of my improved pilot beam. Such beam is of hollow cast metal construction of substantially the same dimensions as 105 would be the case were the prevailing type of beam employed. Beam B differs from this prevailing type in that its central portion, as shown, that lying intermediately the two frame members A, A and A', A', is 110

curved outwardly to conform with the arc of a circle. The radius of such circle may of course be varied, but one of from eight to ten feet will usually prove desirable. This outwardly curved portion is further provided with a horizontal longitudinally extending slot b in which is slidably mounted, transversely of the beam, a short bar C . Rigidly mounted upon the outer end of this bar is a draw-head or coupler pocket C' , and similarly mounted on the other, or rearwardly projecting end of the bar is a plate C^2 . The inwardly directed surfaces of draw-head C' and plate C^2 are curved to conform respectively with the convex and concave faces of the curved beam portion against which they lie. By means of such draw-head and plate, bar C which constitutes in effect the pilot beam of the locomotive, is retained against endwise movement in slot b of the bumper beam, but is free to move from one extremity of said slot to the other. Clearly the effect of the movement described, so far as radius of swing is concerned, is the same as though the pilot beam were actually equal in length to the radius of curvature of the portion of the bumper beam in question. In order that the draw bar may be thus variously positioned without inconvenience or danger to the brakeman two shafts D , bearing hand wheels d are vertically mounted in bumper beam B , one on each side of the aforesaid central curved portion. Upon the lower ends of each such shaft D , but lying within bumper beam B is mounted a sprocket wheel or pocketed sheave d' about which passes a broken chain D' . The ends of this chain are attached by means of suitable clevises d^2 to opposite sides of the draw-head or coupler pocket C' , and a turn-buckle d^3 or the like is inserted in the straight stretch of the chain extending between the two sheaves d' , whereby the tension of such chain may be suitably adjusted as occasion arises. Sheaves d' , as also opening b' through which the chain is admitted within the hollow beam, are all located below the level of the walls forming slot b , so that the stretch of cable above referred to may be wholly contained within such beam also.

Running boards or platforms E are supported from brackets E' attached to the underside of beam B , and as will be evident from an inspection of Fig. 1, a brakeman standing on any one of these platforms will have a hand wheel d within easy reach by a simple turn of which the draw bar of the engine can be swung to register with the draw-bar of the car to be coupled whether such car is standing upon a straight or curved section of track.

The particular type of coupler employed in conjunction with my improved beam construction is a matter of indifference; that chosen for the purpose of illustration is one

of the approved types of automatic coupler now in general use, and fully complying with the requirements of modern railroad legislation. A modification, however, is necessitated in the mechanism whereby the coupler is adapted to be actuated from the side of the car. To this end a lever C^3 is pivotally mounted upon the plate C^2 forming the rear portion of the beam. The forward end of this lever is suitably connected with the lock c^2 of the coupler, so that upon raising and lowering the lever, such lock will likewise be raised and lowered. That such actuation of lever C^3 may be had a shaft C^4 is mounted longitudinally of bumper beam B and upon its upper side, such shaft having its respective ends inclosed and journaled in tubes, or pipe sections, b^2 , supported by standards b^3 , such tubes serving as hand rails for the brakeman standing on platform E . The portion of shaft C^4 intermediate of tubes b^2 lies beneath lever C^3 and is bent so as to form a crank. Rotation of such shaft, which may be effected from either end by means of handles c^4 , will actuate the lever in the manner described.

The operation of the above described improved pilot beam, it is thought, will be sufficiently obvious from the description of the operation of its several parts incidental to the preceding description of their structure. Such beam, it is also thought, is sufficiently illustrative of the general principles involved in my improved draw-gear, to render it unnecessary here to notice all the numerous modifications of which it may be susceptible or which may be necessary to adapt it to other types of locomotives than that here assumed, much more to rolling stock other than locomotives. Only a single such modification has hence been illustrated in the drawings, Figs. 4 and 5. The mode of construction there disclosed illustrates one approved adaptation of my device to a wooden bumper beam such as is frequently found especially in switching engines. The curved portion is here built up by the application of castings F , F' having respectively a convex and concave outer face, to the front and back of the beam F^2 . Fitted to the rear casting F' is a complemental plate f and to the front casting F , a draw head f' of any approved character. A heavy strap f^2 passes around plate f and has its ends attached to draw head f' , whereby there is formed in effect a rigid structure or frame corresponding to the draw bar of the above described construction and like it slidably mounted on a curved beam portion. To assist in sustaining the draw-head, weighted down as it is with the coupler, plate F is preferably formed, with a tongue f^3 and the draw-head with a registering groove f^4 . Mechanism similar to that shown in Figs. 1, 2, and 3 is obviously capable of use with this

construction of pilot beam for positioning the same upon the beam and for operating the coupler proper.

Other modes of applying the principle of my invention may be employed instead of the one explained, change being made as regards the mechanism herein disclosed, provided the means stated by any one of the following claims or the equivalent of such stated means be employed.

I therefore particularly point out and distinctly claim as my invention:

1. In a locomotive or the like, the combination with a transversely disposed beam, 15 of a coupler slidably mounted thereon, said coupler being otherwise unsupported, so as to have a motion of translation therealong.

2. In a locomotive or the like, the combination with a transversely disposed beam, 20 having a portion curved outwardly to conform with the arc of a circle, of a coupler slidably mounted upon and wholly supported by such curved beam portion, so as to have a motion of translation therealong.

25 3. In a locomotive or the like, the combination of the vehicle frame, a transversely disposed bumper beam secured to the end of said frame, said beam having its central portion curved outwardly to conform with the

arc of a circle, a bar mounted on said beam 30 and adapted to bear upon the opposite concave and convex faces of such curved portion, said bar being wholly supported by said beam so as to have a motion of translation therealong, and a coupler borne by the 35 outer end of said bar.

4. In a locomotive or the like, the combination of the vehicle frame, a transversely disposed bumper beam secured to the end of 40 said frame, said beam having its central portion curved outwardly to conform with the arc of a circle, and such central portion being formed with a horizontal longitudinally extending slot, a bar lying in said slot, a draw-head mounted on the outer end of 45 said bar, and a plate mounted on the inner end thereof, said draw-head and plate serving to retain said bar in said slot and having their inwardly directed surfaces respectively curved to conform with the convex and concave faces of such curved beam portion.

Signed by me, this 28th day of February, 1907.

CHARLES C. HOGEN.
